SCREW DRIVER WITH SCREW HOLDING MEANS
Lawrence M. Brown, 931 S. 7th East,
Salt Lake City, Utah
Filed June 23, 1958, Ser. No. 743,881
5 Claims. (Cl. 145—50)

This invention relates to new and useful improvements in screw drivers, and more specifically to a screw driver which is provided with internally disposed screw retaining means.

When starting a screw into a hole, it is necessary that the blade of the screw driver be retained in the kerf of the screw. While this is easily done when both hands are available, one for holding the screw on the screw driver and the other for turning the screw driver, there are many instances where either both hands are not available, or it is impossible to place one's hand in the area where the screw is to be positioned. Normally in order to retain the screw in the proper relationship to the screw driver, there has been provided a pair of claws or spring fingers which slide along the outside of the screw driver shank and engage under the head of the screw to hold the screw on the screw driver blade. These spring fingers have numerous disadvantages which will not be elaborated here. On the other hand, it has been found that if the blade of the screw driver is bifurcated and that there be provided an intermediate blade portion which may be biased with respect to the main blade portions, the biasing of the intermediate blade portion with respect to the remainder of the blade will be sufficient to hold a screw on the screw driver. It is therefore the primary object of this invention to provide a novel screw holding means of the type which uses a turnable intermediate blade portion for biasing a screw relative to the screw driver blade.

Another object of this invention is to provide an improved screw holding means of the type which includes a biasing blade portion, the screw holding means including a torsion member which normally retains the intermediate blade portion in a biased position and there being provided a suitable operator for aligning the intermediate blade portion with the main blade portions so that the entire blade may be positioned in the kerf of a screw and the screw retained on the blade after the operator is released due to the function of the torsion member.

A further object of this invention is to provide an improved screw driver with screw holding means, the screw holding means being of an extremely simple construction and being of such a nature whereby they may be readily retained within a hollow handle of a screw driver.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is an elevational view of the screw driver which is the subject of this invention and shows the general outline thereof;

FIGURE 2 is an enlarged fragmentary sectional view taken substantially upon the plane indicated by the section line 2—2 of FIGURE 1 and shows the specific details of the screw holding means, a portion of the shank of the screw driver being broken away;

FIGURE 3 is an enlarged fragmentary sectional view taken substantially upon the plane indicated by the section line 3—3 of FIGURE 2 and shows the specific connection between a rod of the screw holding means, a torsion member and an extension of the handle which is used to position the screw holding blade portion;

FIGURE 4 is an enlarged transverse sectional view

2

taken substantially upon the plane indicated by the section line 4—4 of FIGURE 2 and shows the manner in which the handle of the screw driver is interlocked with a tubular extension of the shank of the screw driver and the relationship of the torsion member with respect to this tubular extension;

FIGURE 5 is an enlarged fragmentary sectional view taken substantially upon the plane indicated by the section line 5—5 of FIGURE 2 and shows the manner in which the upper end of the torsion member is locked with respect to the tubular extension;

FIGURE 6 is an enlarged end view of the screw driver shank showing the screw holding blade portion disposed in an intermediate position for retaining a screw head in engagement with the screw driver shank.

FIGURE 7 is a view similar to FIGURE 6 and shows the intermediate blade portion aligned with the main blade portions ready for the reception of a screw;

FIGURE 8 is an enlarged perspective view of a modified form of connector for connecting the torsion member to the rod of the screw holding means; and

FIGURE 9 is an enlarged fragmentary longitudinal view taken through a modified form of screw driver and shows a modified form of torsion member.

Referring now to the drawings in detail, it will be seen that there is illustrated the screw driver which is the subject of this invention, the screw driver being referred to in general by the reference numeral 10. The screw driver 10 includes an elongated tubular shank 12 which has a longitudinal bore 14 therethrough. The shank 12 terminates at its lower end in a blade 16. Due to the bore 14, the blade 16 is bifurcated and includes a pair of blade portions 18 which will be considered main blade portions.

Telescoped over the upper end of the shank 12 is an enlarged tubular extension 20. The extension 20 has a longitudinal keyway formed in the upper portion thereof, the keyway being referred to by the reference numeral 22 and being best shown in FIGURE 4. A handle 24 is telescoped over the upper portion of the tubular extension 20 and is interlocked therewith by means of a projection 25 which extends into the keyway 22.

Carried by the screw driver 10 are the screw holding means which are the subject of this invention, the screw holding means being referred to in general by the reference numeral 28. The screw holding means 28 includes an elongated rod 30 which extends through the bore 14 and is rotatably journaled in the shank 12. The rod 30 terminates at the lower end thereof in a blade portion 32 which terminates coplanar with the blade 16 and is disposed intermediate the blade portions 18. The rod 30 extends above the shank 12 and terminates in an offset end 34.

As is best shown in FIGURE 3, the tubular extension 20 is provided with a transverse slot 36. The offset end 34 extends through the transverse slot 36. This transverse slot 36 also serves to vertically position the rod 30 in the shank 12.

Rotatably journaled on the lower portion of the tubular extension 20 is a cylindrical extension 38 of the handle 24. The extension 38 is an operator and has the peripheral surface thereof configured to facilitate the gripping thereof as is best shown in FIGURE 3. The cylindrical extension 38 is provided with a transverse bore 40 which is aligned with the slot 36 and which receives the offset end 34 so that the cylindrical extension 38 is interlocked with the rod 30. Thus by rotating the cylindrical extension 38, the intermediate blade portion 32 may be selectively aligned with the main blade portions 18, as is best shown in FIGURE 7.

In order that the intermediate blade portion 32 may be biased from one position aligned with the blade portions

18 toward a position rotated 180° from the one position and past the position illustrated in FIGURE 6, there is disposed within the tubular extension 20 a torsion member 42 in the form of a flat strip of spring material. The upper end of the torsion member 42 is anchored relative to the tubular extension 20 by means of an inverted U-shaped connector 44 which is telescoped over the upper end of the torsion member 42 and which has ends thereof seated in longitudinal slots 46 formed in transverse alignment in the upper end of the tubular extension 20, as is best shown in FIGURE 5.

Secured to the lower end of the torsion member 42 by means of a transverse pin 48 is a U-shaped connector 50. The U-shaped connector 50 is engaged over the offset end 34 of the rod 30. Thus the opposite ends of the torsion member 42 are anchored to the tubular extension 20 and to the rod 30.

The torsion member 42 is so connected to the rod 30 whereby the intermediate blade portion 32 is normally urged toward the intermediate position illustrated in FIGURE 6 from a position rotated 180° from its normal position by the torsion member 42. When it is desired to place a screw on the screw driver 10, by rotating the cylindrical extension 38, the intermediate blade portion 32 is aligned with the main blade portions 18 as is shown in FIGURE 7. In doing so, it is rotated 180° from its normal position and necessary that torsional stresses be set up in the torsion member 42. Thus when the cylindrical extension 38 is released, the intermediate blade portion 32 will automatically be urged back towards its position of FIGURE 6 by the torsion member 42. This will bias a screw head with respect to the main blade portions 18 and thus retain the screw on the screw driver 10.

Referring now to FIGURE 8 in particular, it will be seen that there is illustrated a modified form of connector which is referred to in general by the reference numeral 52. The connector 52 is a replacement for the connector 50 and is in the form of a circular cross sectional bar of a diameter to be received in the tubular extension 20. The connector 52 has a transverse slot 54 in the upper end thereof in which there is received the lower end of the torsion member 42. A similar, but wider transverse slot 56 is formed in the lower end of the connector 52. The transverse slot 56 is disposed generally at right angles to the transverse slot 54 and receives the offset end 34 of the rod 30.

Referring now to FIGURE 9 in particular, it will be seen that there is illustrated a modified form of torsion member which is referred to in general by the reference numeral 58. The torsion member 58 is in the form of a coil spring having one end 60 extending through an aperture 62 in the tubular extension 20 and the other end thereof in the form of an eye 64 receiving the offset end 34 of the rod 30.

It is to be understood that the two torsion members 42 and 58 will function the same. Both will tend to hold the intermediate blade portion 32 in the position illustrated in FIGURE 6 so as to bias a screw when placed on the screw driver 10 and thus retain the screw in place.

From the foregoing, it will be seen that there has been devised an extremely simple screw holding means wherein all of the components thereof are disposed internally of the screw driver and which are extremely simple in operation and of such a nature so as to be indestructible for all practical purposes.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A screw driver with screw holding means, said screw

driver comprising an elongated tubular shank having a bore therein, said shank terminating at one end in a bifurcated blade for driving a screw and at the other end thereof in a tubular extension having a longitudinal bore formed therein, a handle rigidly secured on said tubular extension, said screw holding means including a rod extending through and rotatably journaled in said bore, said rod terminating at one end in a screw retaining blade disposed intermediate portions of said bifurcated blade and being alignable therewith, an operator connected to the opposite end of said rod for positioning said screw retaining blade, a torsion member disposed within said tubular extension and having one end thereof anchored to said tubular extension, the other end of said torsion member being connected to said rod and urging said screw retaining blade to a position in alignment with said bifurcated blade, said operator being in the form of a cylindrical extension of said handle rotatably journaled on said tubular extension, a transverse slot in said tubular extension aligned with said cylindrical extension, said rod having an offset end portion extending through said slot and secured to said cylindrical extension, said transverse slot being circumferential and the opposite ends thereof consisting of stops limiting the rotation of said offset end portion to 180° between a first position and a second position 180° therefrom.

2. A screw driver with screw holding means, said screw driver comprising an elongated tubular shank having a bore therein, said shank terminating at one end in a bifurcated blade for driving a screw and at the other end thereof in a tubular extension having a longitudinal bore formed therein, a handle rigidly secured on said tubular extension, said screw holding means including a rod extending through and rotatably journaled in said bore, said rod terminating at one end in a screw retaining blade disposed intermediate portions of said bifurcated blade and being alignable therewith, an operator connected to the opposite end of said rod for positioning said screw retaining blade, a torsion member disposed within said tubular extension and having one end thereof anchored to said tubular extension, the other end of said torsion member being connected to said rod and urging said screw retaining blade to a position in alignment with said bifurcated blade, said torsion member being in the form of an elongated strap, a connector securing said strap to said rod, said connector being in the form of an elongated bar having transverse slots in opposite ends thereof, said strap having one end seated in one of said bar slots, said rod having an end portion seated in the other of said bar slots, said transverse slot being circumferential and the opposite ends thereof consisting of stops limiting the rotation of said offset end portion to 180° between a first position and a second position 180° therefrom.

3. A screw driver with screw holding means, said screw driver comprising an elongated tubular shank having a bore therein, said shank terminating at one end in a bifurcated blade for driving a screw and at the other end thereof in a tubular extension having a longitudinal bore formed therein, a handle secured on said tubular extension, said screw holding means including a rod extending through and rotatably journaled in said bore, said rod terminating at one end in a screw retaining blade disposed intermediate portions of said bifurcated blade and being alignable therewith, an operator connected to the opposite end of said rod for positioning said screw retaining blade, a torsion member disposed within said tubular extension and having one end thereof anchored to said tubular extension, the other end of said torsion member being connected to said rod and urging said screw retaining blade to a position in alignment with said bifurcated blade, stop means limiting rotational movement of said rod between a first position with said retaining blade in alignment with said bifurcated blade and a second position rotated 180° from said first position, said torsion member being in the form of an elongated strap, a connector securing said strap

to said rod, said connector being of a U-shape and receiving an end portion of said rod.

4. A screw driver with screw holding means, said screw driver comprising an elongated tubular shank having a bore therein, said shank terminating at one end in a bifurcated blade for driving a screw and at the other end thereof in a tubular extension having a longitudinal bore formed therein, a handle secured on said tubular extension, said screw holding means including a rod extending through and rotatably journaled in said bore, said rod terminating at one end in a screw retaining blade disposed intermediate portions of said bifurcated blade and being alignable therewith, an operator connected to the opposite end of said rod for positioning said screw retaining blade, a torsion member disposed within said tubular extension and having one end thereof anchored to said tubular extension, the other end of said torsion member being connected to said rod and urging said screw retaining blade to a position in alignment with said bifurcated blade, stop means limiting rotational movement of said rod between a first position with said retaining blade in alignment with said bifurcated blade and a second position rotated 180° from said first position, said torsion member being in the form of a coil spring.

5. A screw driver with screw holding means, said screw driver comprising a handle having an elongated tubular shank rigidly secured thereto, said shank having a longi-

tudinal bore formed therein, said shank terminating at one end in a bifurcated blade for driving a screw, said screw holding means including a rod extending through and rotatably journaled in said bore, said rod terminating at one end in a screw retaining blade disposed intermediate portions of said bifurcated blade and being alignable therewith, an operator connected to said rod for rotation of the latter for positioning said screw retaining blade relative to said bifurcated blade, stop means limiting rotational movement of said rod between a first position with said retaining blade in alignment with said bifurcated blade and a second position rotated at least 180° from said first position, a torsion member having one end connected to said rod and the other end connected to said shank for yieldably rotating said rod toward said first position.
